CLAIM

The ornamental design for a convertible bed and suitcase, as shown and described.

DESCRIPTION

FIG. 1 is a perspective view of the convertible bed and suitcase in a closed configuration;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a perspective view illustrating the convertible bed and suitcase in between the closed configuration and an open configuration;

FIG. 9 is a perspective view of the convertible bed and suitcase in the open configuration;

FIG. 10 is front elevational view thereof;

FIG. 11 is a rear elevational view thereof;

FIG. 12 is a right side elevational view thereof;

FIG. 13 is a left side elevational view thereof;

FIG. 14 is a top plan view thereof; and,

FIG. 15 is a bottom plan view thereof.

In the drawings, the broken lines showing a handle wrap in FIGS. 1-6 form no part of the claimed design.

In the drawings, the broken lines on the exterior in FIGS. 1-3, not associated with the handle wrap, depict stitching and form no part of the claimed design.

In the drawings, the broken lines on the interior in FIGS. 8-11 depict boundaries of the claimed design, and form no part thereof.

1 Claim, 13 Drawing Sheets
